CLAIM

The ornamental design of a chart for plotting navigational course, as shown and described.

DESCRIPTION

FIG. 1 is a top plan view of a chart for plotting navigational course showing my new design;
FIG. 2 is a front elevational view, the rear elevational view being identical;
FIG. 3 is a right side elevational view, the left side elevational view being identical; and
FIG. 4 is a bottom plan view thereof.

FIG.1**FIG.2****FIG.3****FIG.4**
